UNITED STATES PATENT OFFICE

128,683

DESIGN FOR A TABLECLOTH OR SIMILAR ARTICLE

Francis Tausend, New York, N. Y., assignor to Felix Tausend & Sons, New York, N. Y., a partnership

Application June 30, 1941, Serial No. 101,805

Term of patent 3½ years

To all whom it may concern:

Be it known that I, Francis Tausend, a citizen of the United States, residing at New York, in the county and State of New York, have invented a new, original, and ornamental Design for a Tablecloth or Similar Article, of which the following is a specification, reference being had to the accompanying drawing, forming part thereof, wherein the figure is a face view of a quarter section of a tablecloth or similar article showing my new design, the other three sections being identical with that here disclosed, arranged in proper relation to complete the tablecloth.

I claim:

The ornamental design for a tablecloth or similar article, substantially as shown and described.

FRANCIS TAUSEND.
